tion of Illinois

Application April 25, 1933, Serial No. 667,845

14 Claims. (Cl. 225—26)

This invention relates to faucets of the kind wherein a viscous syrup is intermixed with carbonated water or the like to dispense a creamy drink.

Many syrups merely contain a natural or artificial liquid flavor dispersed in a saturated solution of sugar and water but other syrups, such as chocolate, contain solid matter. When a fine stream of carbonated water is discharged into a wholly liquid syrup in a faucet it is possible to break up the syrup and so mix the water therewith that a frothy or creamy drink is discharged from the faucet but when the syrup contains solid matter it is difficult to break up the syrup and mix the water therewith in a manner conducive to the production of a creamy drink. One of the objects of my invention is to effectively break up any of the various kinds of syrups and mix carbonated water or the like therewith to produce a frothy creamy drink.

Another object is to first partially break up a syrup and mix it with a quantity of carbonated water in a faucet to reduce the viscosity thereof and to subsequently so introduce a stream of carbonated water into the mixed water and syrup that a frothy creamy drink is dispensed from the faucet.

A further object is to provide a novel faucet wherein two or more streams of carbonated water or the like are discharged into a passage through which a syrup is flowing so as to thoroughly intermix the syrup and water to thereby insure a thorough intermixture of the water and syrup in a manner conducive to the production of a creamy drink prior to discharge thereof from the faucet.

Still further objects are to produce a faucet wherein a stream of water is directed into a passage, through which a quantity of syrup is flowing, in a direction substantially opposite to the flow of the syrup; to regulate the discharge of water into the syrup to control the relative proportions of syrup and water intermixed in the faucet; to regulate the fineness of the stream of water to thereby control the admixture of syrup and water; to direct two or more streams of water into a passage through which a quantity of syrup is flowing in predetermined relation with each other to effect dispersion of the water in the syrup and thereby effectively mix the syrup and water; to flush out the passage, wherein the syrup and water are mixed, after each operation of the faucet to maintain a sanitary condition in the passage and to prevent dripping from the discharge end of the faucet; and

to provide a novel faucet of simple and economical construction and efficient and positive operation.

Selected embodiments of the invention are illustrated in the accompanying drawing wherein

Fig. 1 is a transverse sectional view and in which certain parts are shown in elevation;

Fig. 2 is a longitudinal sectional view taken substantially on the line 2—2 on Fig. 1;

Fig. 3 is a view similar to Fig. 1 showing a modified form of the invention;

Fig. 4 is another view similar to Fig. 1 showing a further modified form of the invention;

Fig. 5 is a horizontal sectional view taken substantially on the line 5—5 on Fig. 4; and

Fig. 6 is a view similar to Fig. 5 showing a further modified form of the invention.

The preferred form of faucet illustrated in the accompanying drawing comprises a substantially cylindrical body 7 having a boss 8 projecting radially therefrom substantially medially in the extent thereof. Another radially extending boss 9 providing a nozzle 10 projects from the body 7 medially in the extent thereof and at right angles to the boss 8. A flange 10 is provided at the free end of the boss 8 and is adapted to be connected to a suitable fixture. A syrup passage 11 and a water passage 12 extend through the boss 8 and syrup and water supply pipes are respectively connected to the outer ends of the passages and these connections are concealed by the flange 10.

Recesses 13 and 14 are provided at opposite ends of the body 7. A washer 15 is disposed at the bottom of the recess 13 and a tumbler 16 seats thereagainst. The tumbler includes a diametrically extending rib 17 seated in a diametrically extending bifurcation in the connector 18 which includes a neck 19 extended through an opening 20 in the nut 21 secured to the adjacent end of the body 7 and holding the connector 18 in position. A handle 22 is secured on the connector 19 by the nut 23. A bolt 24 extends through the nut 23 and the connector 19 and engages the rib 17 to force the tumbler 16 into tight engagement with the washer 15.

A passage 25 is provided in the tumbler 16 and terminates in ports disposed in the face of the tumbler engaging the washer 15. A passage 26 extends from the inner end of the passage 11 to a port in the washer 15. Another passage 27 extends from a port in the washer 15 and through body 7 to the upper end of the outlet passage 28 which extends through the nozzle 10. The tumbler 16 may be rotated to register the

ports therein with the ports at the ends of the passages 26 and 27 whereupon syrup flows from the passage 11 through the passage 26, passage 25 and passage 27 to the outlet passage 28. A washer 29 is provided at the bottom of the recess 14 and the face of a tumbler 30 is engaged therewith. The tumbler 30 includes the diametrically extending rib 31 seated in a diametrically extending bifurcation in the connector 32. The connector 32 is retained in position by a nut 33 engaging the adjacent end of the body 7. A handle 34 is secured to the connector 32 in the same manner as that in which the handle 22 is secured to the connector 18. A bolt 35 similar to the bolt 24, forces the tumbler 30 into tight engagement with the washer 29. A passage 36 extends from the inner end of the water passage 12 through a medially located port in the washer 29 which communicates with a centrally located port 37 in the tumbler 30. Three ports 38, 39 and 40 are provided in the face of the tumbler 30 engaging the washer 29 and communication is established between these ports and the port 37 through a passage 41 in the tumbler 30. The ports 38, 39 and 40 are adapted to successively register with a port in the washer 29 at the end of a passage 42 which extends through the body 7 to a passage 43 in the body and which extends through the nozzle 16 parallel to but spaced from the passage 28. Communication between the outlet passage 28 and the water passage 43 is established in a manner to be described so that water flowing into the passage 43 may be discharged into the passage 28 to be intermingled with syrup flowing through said passage 28 from the passage 27. Another passage 44 extends through the tumbler 30 from the port 37 to a port 45 in the face of the tumbler engaging the washer 29. The port 45 is adapted to register with a port in the washer 29 at one end of a passage 45' leading to the inner end of the outlet passage 28. The handles 34 and 22 are interconnected by a nut 46 so that they may be operated simultaneously. A pin 47 extends from the body 7 above the boss 8 and another pin 48 extends from the body 7 in spaced relation with the pin 47. The handles 22 and 34 are enlarged to provide a boss 49 engageable with the pins 47 and 48. A ball handle 50 is provided above the nut 46 to facilitate operation of the handles. When the boss 49 is engaged with the pin 47, the tumblers 16 and 30 are so disposed that flow of syrup through the passage 25 is closed off and flow of water through port 37, passage 41 and ports 38, 39 and 40 and passage 44 and port 45 is closed off. However, when the handle 50 is grasped and the boss 49 is moved from engagement with the pin 47 toward and into engagement with the pin 48, syrup and water flow into the passage 28. The port at the end of passage 45' is so located that immediately following disengagement of the boss 49 from the pin 47, the port 45 moves into registration therewith and water flows from passage 36 through port 37, passage 44, port 45 through passage 45' into the outlet passage 28. At this time no syrup is being discharged from the port 27 and the effect of this discharge of water is to flush out the outlet passage 28. After the port 45 moves from registration with the port at the end of passage 45' and upon continued movement of the handle 50, the port 38 moves into registration with the port at the end of passage 42 and at this time the ports at the end of the passage 25 will be slightly

in registration with the ports at the ends of passages 26 and 27 so that a small quantity of syrup flows into the outlet passage 28. It will be noted that the port 38 is of restricted size and hence only a small quantity of water flows into the passages 42 and 43 and the outlet passage 28. As the handle 50 continues to move, the ports at the end of the passage 25 move into further registration with the ports at the ends of passages 26 and 27 and hence the quantity of syrup flowing into the outlet passage 28 is increased and at this time the port 39 moves into registration with the port at the end of passage 42 and a greater quantity of water flows into the passage 28 since the port 39 is larger than the port 38. At the time the boss 49 engages the pin 48, the ports at the end of the passage 25 are in full registration with the ports at the ends of passages 26 and 27 and there is an unrestricted flow of syrup into the outlet passage 28, and at this time the large water port 40 is in registration with the port at the end of passage 42 which affords unrestricted flow of water into the passage 28. The graduated size of the ports 38, 39 and 40 permits flow of water to the outlet passage 28 in direct proportion to the quantity of syrup flowing thereto through the passage 27. When the handle 50 is grasped and the boss 49 is disengaged from the pin 48 and moved toward the pin 47, the registration of the ports at the end of the passage 25 with the ports at the ends of passages 26 and 27 is successively diminished and the successively restricted ports 39 and 38 successively register with the port at the end of passage 42 so that as the flow of syrup is reduced the flow of water is likewise reduced. Immediately prior to the engagement of the boss 49 with the pin 47, the port 45 registers with the port at the end of passage 45'. At this time flow of syrup into the outlet passage 28 is closed off and consequently only water flows thereto and this water serves to flush out the outlet passage to maintain this passage in a sweet and sanitary condition and to prevent drippage from the discharge end thereof.

A flushing faucet of the above described kind is disclosed in my Patent No. 1,930,461, patented October 17, 1933, and is the preferred type of faucet with which my invention is to be used although it is to be understood that my invention might be used in connection with any faucet providing for the simultaneous discharge of syrup and water without departing from the spirit and scope of the invention.

The invention herein particularly relates to the manner in which water flowing into the passages 42 and 43 is introduced into the outlet passage 28 and the invention particularly resides in thoroughly intermixing syrup flowing from the passage 27 into the outlet passage 28 with water introduced into this outlet passage. The invention particularly resides in thoroughly intermixing a heavy syrup and particularly one containing solid matter (chocolate syrup being an example) with carbonated water so as to produce a soda. It will be noted by referring to Figs. 1, 3 and 4 that a plug 51 is inserted into the outer end of the passage 43 to effectively close off this passage, the length of this plug depending upon the location of the passages interconnecting the passages 43 and 28.

In the form of the invention illustrated in Figs. 1 and 2 provision is made for discharging a fine stream of carbonated water into the outlet passage 28 in a direction substantially opposite to

the flow of syrup through this outlet passage. To this end an inclined port 52 is provided which extends at an angle to the bore of the passage 28 and the port 52 is inclined upwardly. A boss 53 is provided on the side wall of the nozzle and a needle valve 54 is arranged therein to control flow of water through the port 52. The needle valve 54 is mounted in an opening 55 extending through the boss 53 across the passage 43 to the port 40. The opening 55 is tapped at 56 to receive the screw-threaded periphery of the needle valve and this mounting permits adjustment of the needle valve relative to the port 52 to control water flow through said port. The stem of the needle valve extends through suitable packing 57 arranged in the enlarged portion 58 of the opening 55, and the packing is held in position by a nut 59 mounted in the outer end of the opening 55 and having a recess 60 therein to receive the end of the needle valve so as to conceal it. The opening 55 terminates in a pocket 61 which communicates with the passage 43 and the port 52 and water flowing through the passage 43 enters the pocket 61 from whence it flows past the needle valve 54 through the port 52 into the outlet passage 28. This water is discharged in the form of a fine stream which impinges against syrup flowing down through the outlet passage 28. This fine stream of water tends to break up the syrup and as the water mixes with the syrup the viscosity is reduced and this intermixed syrup and water continues to flow down through the outlet passage 28. A restricted port 62 extends between the passage 43 and the outlet passage 28. This port is disposed below the port 52 and water flows from the passage 43 through the port 62 into the outlet passage 28 in the form of a fine stream. The syrup and water intermixed in the vicinity of the port 52 flows into alignment with the fine stream of water discharged from the port 62 and this fine stream of water further intermixes the water and syrup and produces a creamy drink which is discharged from the lower end of the outlet passage 28. I have found that by spacing the water ports in the manner in which the ports 52 and 62 are spaced I am enabled to more thoroughly intermix heavy syrups with water and particularly those containing solid matter and so as to produce a creamier drink than is possible when only one stream of water is mixed with the syrup.

In Fig. 3 a modified form of the invention is shown. Herein two ports 63 and 64 open into the outlet passage 28 and these ports are arranged in spaced relation one above the other. These ports respectively communicate with pockets 63' and 64' which communicate with the water passage 43 and in this instance flow of water through each of the ports is controlled by a needle valve substantially similar to the needle valve 54, the needle valve 65 controlling water flow through the port 63 and the needle valve 66 controlling water flow through the port 64. Neither the port 63 nor the port 64 is inclined upwardly but I have found that this arrangement produces a thorough intermixture of the syrup and water and as one fine stream of water is mixed with the syrup prior to the time another fine stream of water is mixed therewith and a satisfactory creamy drink is discharged from the passage 28.

Not all syrups contain solid matter and even those syrups which contain solid matter may be intermixed with water so as to produce a creamy drink provided the admixture of the water and syrup is thorough prior to discharge of the syrup and water from the nozzle. I have described how

a creamy drink can be produced by discharging one stream of water into the syrup prior to the time another stream of water is discharged thereinto. However, I have found that by discharging streams of water so that one stream impinges on the other a thorough dispersion of the water results and that water so dispersed thoroughly intermixes with syrup flowing through the passage into which the water is discharged so that a creamy drink results.

In Figs. 4 and 5 I have illustrated one manner of discharging two streams of water into a passage so as to impinge one on the other whereby the water will be thoroughly intermixed with the syrup. In this instance I provide two ports 67 and 68 which are disposed in the same horizontal plane but in diametrical opposition to each other. The port 67 opens into a pocket 69 and communication between this pocket and the water passage 43 is established through a passage 70. The flow of water through the port 67 is regulated by a needle valve 71 substantially similar to the needle valve 54. The port 68 opens into a pocket 72 and communication between this pocket and the water passage 43 is established through a passage 73. A needle valve 74 similar to the needle valve 54 controls water flow through the port 68. Preferably a drill is passed through the boss 9 to drill the ports 67 and 68 at the same time to insure alignment thereof. Since the ports are aligned one with the other, the fine streams of water discharged from these ports in opposition to each other impinge one on the other so that the water is violently dispersed in all directions and hence this water thoroughly intermixes with syrup flowing through the passage 28 which produces a creamy drink.

In Fig. 6 a modified form of the invention illustrated in Fig. 5 is shown and herein two ports 75 and 76 are provided which are disposed in the same horizontal plane but which open into the passage 28 at right angles to each other. The port 75 leads to a pocket 77 and communication between the pocket 77 and the water passage 43 is established through the passage 78. A needle valve 79 controls the flow of water through the port 75. The port 76 leads to a pocket 80 and communication between the water passage 43 and the pocket 80 is established through the passage 81. A needle valve 82 controls the flow of water through the port 76. The needle valves 79 and 82 are both substantially similar to the needle valve 54. Fine streams of water flowing from the ports 75 and 76 impinge one on the other and the water is violently dispersed so as to be thoroughly intermingled with syrup flowing through the passage 28 and this insures the discharge of a frothy creamy drink from the outlet passage 28. It will be noted that the syrup is introduced into the outlet passage 28 adjacent the inner end thereof and that the intermixed syrup and water flow from the end of the passage 28 opposite that whereat the syrup is introduced into said passage and therefore the streams of water are introduced into the passage intermediate the outlet end of the passage and the place whereat the syrup is introduced thereto so that the intermixture of syrup and water occurs during the flow of the syrup through the outlet passage and toward the outlet end thereof.

I have provided a faucet embodying a passage through which a syrup is caused to flow and I have shown different ways for introducing streams of water into this passage to be thoroughly intermingled with syrup flowing therethrough.

The streams of water may be introduced into the passage one in advance of the other so that water and syrup may be first intermingled and then this thoroughly intermingled water and syrup 5 may be churned by the introduction of the second fine stream of water which I have found produces a creamy drink even where a heavy syrup containing solid matter is caused to flow through the passage into which the streams of water 10 are discharged. The production of a creamy drink may be enhanced by discharging one or both of the streams of water into the passage in a direction substantially opposite to the flow of syrup through the passage for I have found that 15 this increases the intermixing of the syrup and water in such a way as to produce the desired frothy and creamy drink. However, a thorough intermixture of syrup and water may be obtained by discharging two or more streams of 20 water into the passage in such a way that the streams of water impinge one on the other for this disperses the water throughout the passage and insures intermixture thereof with the syrup.

In the faucet selected for showing and describing the invention, the liquids are intermixed in the upper portion of the outlet passage which becomes for this purpose a mixing chamber and from this chamber the intermixed liquids are discharged through the lower end of the passage, 25 and while the passage as shown is tubular and continuous in form, it may obviously be differently shaped to provide the mixing chamber and discharge in adapting the invention for other faucets or for other purposes. I have also shown and described means for flushing the outlet passage to maintain it in a sanitary condition and to prevent drippage but, as herein indicated, the invention is not restricted to this combination and may be embodied in faucets of other kinds. 30 Changes in the form and construction and arrangement of parts and modifications thereof may be made to enable my invention to be used in different kinds of faucets and for different purposes for which it is or may be adapted, and I 35 reserve the right to make all such changes and modifications as fall within the scope of the following claims.

I claim:

1. A faucet for intermixing syrup and water to 50 provide a creamy drink and having a body adapted to be secured to a fixture or the like, a boss on said body having a vertically extending outlet passage therein and a syrup port at the upper end of and opening into said passage, said boss also having a water passage therein and a plurality of branch passages leading from the water 55 passage and providing a plurality of restricted ports opening into said outlet passage and adapted to admit a plurality of fine streams of water 60 into the outlet passage intermediate the upper and lower ends thereof, and valve means operable to effect simultaneous flow of syrup to the syrup port and water to the water ports whereby water admitted in the plurality of fine streams into the outlet passage and the syrup flowing therethrough from the syrup port is thoroughly intermixed with the syrup to produce a creamy drink.

2. A faucet for intermixing syrup and water to 70 provide a creamy drink and having a body adapted to be secured to a fixture or the like, a boss on said body having a vertically extending outlet passage therein and a syrup port at the upper end of and opening into said passage, said boss also having a water passage therein and a plurality 75 of branch passages leading from the water pas-

sage and providing a plurality of restricted ports opening into said outlet passage in spaced relation with each other and adapted to admit a plurality of cooperating fine streams of water into said outlet passage intermediate the upper and lower ends thereof, and valve means operable to effect simultaneous flow of syrup to the syrup port and water to the water ports whereby the plurality of fine streams of water cooperate with each other and effect thorough intermixture of the water 10 with syrup flowing through said outlet passage from said syrup port and produce a creamy drink.

3. A faucet having an outlet passage and valve means for controlling the flow of syrup and water into said passage, means for admitting the syrup 15 into said passage, and means for admitting the water under pressure into said passage simultaneously at more than one position whereby a plurality of streams of water are admitted into the outlet passage to break up the syrup and facilitate intermixture of syrup and water in said 20 passage and produce a creamy drink.

4. A faucet having an outlet passage and valve means for controlling the flow of syrup and water into said passage, means for admitting the syrup 25 into the passage adjacent the innermost end thereof, and means for admitting the water under pressure into said passage simultaneously at a plurality of positions spaced longitudinally of the passage and distributed therealong intermediate 30 the inner and outer ends of the passage whereby water admitted at the innermost of the positions reduces the viscosity of the syrup to facilitate the mixture with the syrup of water admitted at the outermost of the positions and produce a creamy 35 drink.

5. A faucet having an outlet passage and valve means for controlling the flow of syrup and water into said passage, means for admitting the syrup into said passage, and means for admitting the 40 water into the passage in a plurality of fine streams directed to impinge one upon the other whereby the water is dispersed throughout the passage and intermixture thereof with the syrup to produce a creamy drink is facilitated.

6. A faucet having an outlet passage and valve means for controlling the flow of syrup and water into said passage, means for admitting the syrup into the passage adjacent the innermost end thereof, and means for admitting the water under pressure into said passage in fine streams at a plurality of positions spaced longitudinally of the passage and distributed therealong intermediate the inner and outer ends of the passage whereby water admitted at the innermost of the positions reduces the viscosity of the syrup to facilitate mixture with the syrup of water admitted at the outermost of the positions and produce a creamy drink, the fine stream of water admitted at at 50 least one of said positions being inclined relative to the axis of the passage to additionally facilitate the intermixture of syrup and water.

7. A faucet having an outlet passage and valve means for controlling the flow of syrup and water into said passage, means for admitting the syrup into the passage adjacent the innermost end thereof, and means for admitting the water under pressure into said passage in fine streams at a plurality of positions spaced longitudinally of the passage and distributed therealong intermediate the inner and outer ends of the passage, the fine stream of water admitted at the innermost of the positions being inclined relative to the axis of the passage and serving to break up and reduce the viscosity of the syrup to facilitate the 60 65 70 75 80 85 90 95 98

mixture with the syrup of water admitted at the outermost of the positions and produce a creamy drink.

8. A faucet having an outlet passage and valve means for controlling the flow of syrup and water into said passage, means for admitting the syrup into said passage, means for admitting the water under pressure into said passage simultaneously at more than one position whereby a plurality of fine streams of water are admitted into the outlet passage to break up the syrup and facilitate intermixture of syrup and water in said passage and produce a creamy drink, and means at least one of said positions for regulating the flow of water into said passage at said positions.

9. A faucet having an outlet passage and valve means for controlling the flow of syrup and water into said passage, means for admitting the syrup into said passage, means for admitting the water under pressure into said passage simultaneously at more than one position whereby a plurality of fine streams of water are admitted into the outlet passage to break up the syrup and facilitate intermixture of syrup and water in said passage and produce a creamy drink, and adjustable means at each of said positions for regulating the flow of water into said passage at said positions.

10. A faucet having an outlet passage and means for controlling the flow of syrup and water into said passage, means for admitting the syrup into said passage, and said faucet having at least two ports directed toward a common point in said outlet passage for admitting the water under pressure into said passage for intermixture in said passage with the syrup to produce a creamy drink.

11. A faucet having an outlet passage and means for controlling the flow of syrup and water into said passage, means for admitting the syrup into said passage, and said faucet having a pair of ports arranged in opposition to each other for admitting the water under pressure into said

passage for intermixture in said passage with the syrup to produce a creamy drink.

12. A faucet having an outlet passage and means for controlling the flow of syrup and water into said passage, means for admitting the syrup into said passage, and said faucet having radially disposed ports extending in angular relation toward a common point in said passage for admitting the water under pressure into said passage for intermixture in said passage with the syrup to produce a creamy drink.

13. A faucet having an outlet passage and valve means for controlling the flow of syrup and water into said passage, means for admitting the syrup into said passage, means for admitting the water under pressure into said passage simultaneously at more than one position whereby a plurality of fine streams of water are admitted into the outlet passage to break up the syrup and facilitate intermixture of syrup and water in said passage and produce a creamy drink, and means for flushing said outlet passage upon each operation of said valve means to admit syrup and water into said outlet passage.

14. A faucet having an outlet passage and valve means for controlling the flow of syrup and water into said passage, means for admitting the syrup into the passage adjacent the innermost end thereof, means for admitting the water under pressure into said passage simultaneously at a plurality of positions spaced longitudinally of the passage and distributed therealong intermediate the inner and outer ends of the passage whereby water admitted at the innermost of the positions reduces the viscosity of the syrup to facilitate the mixture with the syrup of water admitted at the outermost of the positions and produce a creamy drink, and other means for admitting water to said passage to flush out said passage upon each operation of said valve means.

WILLIAM C. BUTTNER.
